(57) **CLAIM**

The ornamental design for a modular robotic sensor platform, as shown.

DESCRIPTION

The invention described herein may be manufactured, used and/or licensed by or for the United States Government.

FIG. 1 is a top view of the modular robotic sensor platform thereof;

FIG. 2 is a left side view of the modular robotic sensor platform, thereof;

FIG. 3 is an alternate embodiment of the left side view of the modular robotic sensor platform, thereof;

FIG. 4 is a front view of the modular robotic sensor platform, thereof;

FIG. 5 is a bottom view of the modular robotic sensor platform, thereof;

FIG. 6 is an isometric view of the modular robotic sensor platform, thereof;

FIG. 7 is a rear view of the modular robotic sensor platform, thereof;

FIG. 8 is a left side view of the modular robotic sensor platform, thereof;

FIG. 9 is a right side view of the modular robotic sensor platform, thereof; and,

FIG. 10 is a front view of the modular robotic sensor platform, thereof.
